(57) **CLAIM**

I claim the ornamental design for a three flexibility rotation and vision equipment, as shown.

DESCRIPTION

FIG. 1 is a top plan view of the three flexibility rotation equipment of the present invention;

FIG. 2 is a front elevation view thereof;

FIG. 3 is a left side view thereof;

FIG. 4 is a rear elevation view thereof;

FIG. 5 is a bottom plan view thereof;

FIG. 6 is a right side view thereof showing the limit or a movable region above;

FIG. 7 is a right side view thereof showing the limit or a movable region down;

FIG. 8 is a rear elevation thereof showing the limit of the movable region to the objective left;

FIG. 9 is a rear elevation thereof showing the limit of the movable region to the objective right;

FIG. 10 is a front elevation thereof showing a first of three states of use thereof;

FIG. 11 is a right side view thereof showing the first state of use thereof;

FIG. 12 is a front elevation thereof showing a second of three states of use thereof;

FIG. 13 is a right side view thereof showing the second state of use thereof;

FIG. 14 is a front elevation thereof showing a third of three states of use thereof;

FIG. 15 is a right side view thereof showing the third state of use thereof;

FIG. 16 is a top plan view of the vision equipment according to the present invention;

FIG. 17 is a front elevation view thereof;

FIG. 18 is a right side view thereof;

FIG. 19 is a left side view thereof;

FIG. 20 is a rear elevation view thereof;

FIG. 21 is a bottom plan view thereof;

FIG. 22 is a right side view thereof showing the limit of a movable region above;

FIG. 23 is a right side view thereof showing the limit of a movable region down;

FIG. 24 is a rear elevation thereof showing a visualizing body that is for visualizing an object turning and showing the limit of the movable region in a first position;

FIG. 25 is a rear elevation thereof showing a visualizing body that is for visualizing an object turning and showing the limit of the movable region in second position;

FIG. 26 is a rear elevation thereof showing a visualizing body that is for visualizing an object turning and showing the limit of the movable region in third position;

FIG. 27 is a rear elevation thereof showing the limit of the movable region to a visualizing body left in a first position;

FIG. 28 is a rear elevation thereof showing the limit of the movable region to a visualizing body right in a first position; FIG. 29 is a left elevation thereof showing the limit of the movable region to a visualizing body left in a second position;

FIG. 30 is a rear elevation thereof showing the limit of the movable region to a visualizing body right in a second position;

FIG. 31 is a front elevation thereof showing the use state of vision equipment;

FIG. 32 is a right side thereof showing the use state of vision equipment;

FIG. 33 is a rear elevation thereof showing a visualizing body that is for photographing an object turning and showing the limit of the movable region in a first position;

FIG. 34 is a rear elevation thereof showing a visualizing body that is for photographing an object turning and showing the limit of the movable region in second position;

FIG. 35 is a rear elevation thereof showing a visualizing body that is for photographing an object turning and showing the limit of the movable region in third position;

FIG. 36 is a rear elevation thereof showing the limit of the movable region to a visualizing body for photographing an object left in a first position;

FIG. 37 is a rear elevation thereof showing the limit of the movable region to a visualizing body for photographing an object right in a first position;

FIG. 38 is a rear elevation thereof showing the limit of the movable region to a visualizing body for photographing an object left in a second position; and,

FIG. 39 is a rear elevation thereof showing the limit of the movable region to a visualizing body for photographing an object right in a second position.

FIGS. 1-15 show a design for three flexibility rotation equipment made to rotate objects, such as a camera and a lever, with three degrees of flexibility.

FIGS. 16-39 show a design for vision equipment which visualize or photograph an object.

The broken lines in the drawings show environmental structure and form no part of the claimed design.
